UNITED STATES PATENT OFFICE.

THEODORE DOMINICK, OF WENATCHEE, WASHINGTON.

HATCHET.

Application filed January 4, 1929. Serial No. 330,367.

The present invention relates to hatchets and more specifically to an improved construction for hatchets primarily intended for use in making fruit boxes and the like.

5 In the manufacture or making of fruit boxes such as apple, pear, orange and peach boxes, a special type of hatchet is used which is provided with a knurled driving face for striking the nails. This knurled driving face is provided so that the nail will not slip to one side, nor the poll slip off the nail head in case the driving blow is not delivered squarely. This knurled face is also used in starting the nails, and for speed production, the nailer 10 or operator ordinarily holds a number of nails between his fingers, requiring that the hatchet be held at an angle to the nail shank to eliminate starting or hitting of more than one nail. After starting one of the nails with the 15 hatchet at an angle to avoid starting more than one nail, the hatchet must be twisted by the operator's wrist to an upright position for driving the nail home.

It is therefore the primary object of the 20 present invention to provide an improved box making hatchet having a construction to permit of one nail of a group of nails held between the operator's fingers, to be started without requiring any twist or tilting of the 25 hatchet at an angle in order to start one of the nails.

A further object of the invention is to provide an improved starter hatchet which 30 will permit starting and driving blows for the nails being done with like motions of the hatchet and thus tending to speed up production without undue exertion on the part of the operator.

A still further object of the invention is to 35 provide a hatchet of this character embodying a starting lug or projection for starting the nails, and which lug or projection will not interfere with proper use of the driving face for driving the nails home.

40 Other objects and advantages of the invention will be apparent during the course of the following detailed description, taken in connection with the accompanying drawing forming a part of this specification and in 45 which drawing:

Figure 1 is an end plan view of the improved starter hatchet and showing the manner of use for starting one nail of a group of nails held between the operator's fingers with the hatchet head in longitudinal alignment 50 with the nail shank.

Figure 2 is a side elevation of the hatchet head looking at the left side thereof or that side provided with the starter lug or projection.

60

Figure 3 is a view looking at the hatchet from the driving face thereof.

In the drawing wherein similar reference characters designate corresponding parts thruout the several views, the hatchet has 65 been shown of the usual outline of conventional box making hatchets provided with the blade 5 and poll 6 between which is arranged the usual eye 7 for receiving the handle 8. As in usual construction of a hatchet of this 70 character the driving face 9 is slightly convex and suitably knurled so that the nail will not slip to one side or the hatchet slip off the nail head in case the driving blow is not delivered squarely. This knurled driving face also 75 permits of one of the nails being started with the hatchet head at an angle, or the driving face at an angle to the nail shank, without slipping.

In the improved construction of the hatchet 80 shown, the poll 6 has integrally formed along one side thereof, a substantially V-shaped lug or projection 10 having its outer surface diverging from one edge of the driving face 9 toward the eye 7 as clearly illustrated in Figure 1. Provided to extend transversely of the outer diverging surface of the lug 10 preferably from the face 9 to the eye 7, 85 is a series of beveled notches 12 each forming a driving surface 14 facing toward the driving face 9 and extending substantially parallel therewith. By observing Figure 1 it will 90 be seen that the driving surfaces 14 are offset outwardly with respect to the longitudinal axis of the poll 6 from the face 9 to the eye 7. 95

In use of the hatchet for starting one of a number of nails held between the operator's fingers, a light tap or blow may be made by the hatchet with the longitudinal axis of the hatchet head parallel with the nail shank so 100 that one of the driving surfaces 14 at the outer inclined surface of the starting lug will engage the head of the nail designated at "a" and start the nail into the box B. The starting blow is delivered so that the driving face 9 105 passes to one side of the nail to be started and as any one of the driving surfaces 14 engage the nail head the nail will be started into the box. By observing Figure 1 it will be seen that the starting blow delivered to the nail 110 "a" will not cause any of the remaining nails held between the operator's fingers to be

started. As will readily be understood, the object in holding a number of nails between the fingers is to speed up the work and eliminate picking the nails up individually. It will be noted that with the improved type of hatchet that the starting blows or taps and also the driving blows for driving the nails home are both made with the hatchet head in one position and thus eliminate exertion of 10 arm and wrist twisting motions for first starting and then driving the nails.

While the nail starting improvement has been shown incorporated in a hatchet construction it will readily be apparent that the 15 starting lug may equally well be applied to the poll of hammers or various other driving implements. While the illustration shows the starting lugs arranged at the left side of the poll for rendering the hatchet adaptable 20 for use by a right hand operator, it will readily be apparent that the starting lug may equally well be applied to the right side of the poll for use by a left hand operator. It will also be understood that the hatchet may be 25 used for various other purposes other than the making of fruit boxes.

From the foregoing description it will be apparent that a novel and improved construction for driving implements has been 30 provided embodying improved means whereby nails may be started and driven without requiring tilting or twisting of the implement in the operator's hand; and which arrangement permits of one nail of a group of nails

held between the operator's fingers to be 35 started without starting or hitting other nails held between the fingers.

Changes in detail may be made to the form of invention herein shown and described, without departing from the spirit of the in- 40 vention or the scope of the following claims.

I claim:

1. A hatchet including a poll having a wedge-shaped lug formed along one side thereof providing an inclined outer surface 45 diverging from one edge of the driving face of the poll toward the inner end of the poll, said inclined surface being formed with beveled notches each providing a driving surface facing in a like direction as the driving face 50 of the poll and offset with respect to the longitudinal axis of the poll.

2. In a hatchet embodying a head including a poll provided with a driving face, and an eye at the inner end of the poll, a nail starting lug formed integral with and at one side of the poll and having an outer surface diverging from one edge of the driving face toward said eye, said lug at its outer diverging surface being provided throughout its length with 60 a series of transverse notches each providing a driving surface facing in a like direction as the driving face of the poll, said driving surfaces being offset outwardly with respect to the longitudinal axis of the poll from the 65 driving face toward the eye.

THEODORE DOMINICK.
